INVENTOR

Joseph Kirby

UNITED STATES PATENT OFFICE.

JOSIAH KIRBY, OF CINCINNATI, OHIO.

BUNG.

SPECIFICATION forming part of Letters Patent No. 292,826, dated February 5, 1884.

Application filed November 5, 1883. (No model.)

To all whom it may concern:

Be it known that I, JOSIAH KIRBY, of Cincinnati, Hamilton county, Ohio, have invented certain new and useful Improvements in Bungs, 5 of which the following is a specification.

My invention relates to that class of bungs in connection with which a ventilator is to be employed; and its object is to provide a bung the central portion of which may be readily 10 driven into the cask by the ventilator without danger of splitting off the peripheral bottom portion of the bung, and which, before said central portion is so driven in, will tightly close the bung-hole of the cask.

15 Referring to the drawings forming part of this specification, Figure 1 represents the top face, and Fig. 2 the bottom face, of a bung, showing the preferred form of the incisions in said faces. Fig. 3 is a diametrical section of 20 the bung, taken at the line $x x$ of Fig. 1, as it appears before the central portion is driven out. Fig. 4 represents the same section, the central portion being partly driven out. Fig. 25 5 represents the bottom face of a bung, showing a different location and shape of incisions in said bottom face. Fig. 6 represents one of the various styles of bung now in use, illustrating the defective feature of this class of bungs, which is overcome by my invention.

30 A is the bung, cut from wood, the grain of which runs parallel to the bung. The upper face of the bung may be provided with the usual recess or incision, C, formed in any of the known ways, and where, as is sometimes 35 the case, this recess is wanting, or is not sufficiently deep to accomplish, in connection with the incisions hereinafter described as made in the lower face of the bung, the purposes of my invention, I make a circular incision, a, extending, preferably, more than half-way through 40 the bung, as shown in Fig. 3. In the bottom face of the bung are formed the incisions b, preferably semicircular in shape, and which are preferably placed transversely to the grain 45 of the wood, and the distance between these incisions in the lower face of the bung being preferably slightly greater than the diameter of the circular incision or recess a in the top face of the bung, the wood between the ends of 50 the said incisions in the lower face of the bung

remaining intact and adding great strength to the bung.

In the Letters Patent No. 268,026, dated November 28, 1882, granted to me, for improvements in bungs, similar incisions to those already herein described were formed in the upper and lower ends or faces of the bung; but, as specified in that patent, the lower end of the incision or incisions formed in the upper portion of the bung and upper end of the 55 incisions formed in the lower face of the bung were extended to one and the same plane—that is to say, in a plane substantially parallel to the faces of the bung.

The invention which is the subject of the 60 present application for Letters Patent consists in preserving and retaining a very thin disk of uncut wood lying in a plane substantially parallel to the faces of the bung, at the same time employing the upper recess or incision, 65 a, and the lower incisions, b b. Thus in the present invention the lower end of the incision from above and the upper ends of incisions from below do not quite reach to a common plane, but a quite thin disk of uncut wood of 70 75 the diameter of the bung is between the respective planes in which the said lower and upper ends are respectively located. In practice I have found such a bung will utilize all of the advantages derived from the said incisions, and at the same time afford the further 80 advantage that the cutters entering opposite sides of the bung shall not and need not exactly or fully reach a common plane. Furthermore, a lower central portion, B, of the bung 85 is more firmly held in position in the bung, and integral therewith while in use as a bung.

When the bung is to be used as a bushing, the rear end of a ventilator is introduced through the outer or upper face of the bung, 90 and the ventilator being driven through the bung and into the cask carries with it the portion B, as shown in Fig. 4.

In the bungs heretofore in use, in which circular or continuous incisions have been 95 formed, quite a thick web of wood is necessarily left, which has to be broken through by the ventilator; and in very many instances this causes the bung to be split in the manner shown in Fig. 6, leaving but a very imperfect 100

packing for the ventilator, and thereby causing leakage; but by my invention the wood remaining intact between the incisions *b* in the bottom face of the bung enables me to penetrate the bung from opposite sides to such an extent that the planes of the bottoms of the incisions in the opposite sides may nearly meet without detriment to the bung, as the dampness closes up the incisions and prevents leakage, and thus leaving the portion of the grain of the wood to be broken across so thin that all danger of splitting off the bottom portion of the bung is removed, as the central portion, *B*, is readily split from the peripheral portion along the dotted lines in Fig. 2, and the central portion or plug thus driven out assumes the shape shown in Fig. 4, and the peripheral portion of the bung left in the bung-hole or bushing remains perfect for its entire thickness, and forms a perfect packing for the ventilator.

Instead of forming the incisions *b* in the bottom face of the bung substantially transversely to the grain of the wood, as above described, they may be formed parallel to each other, as shown in Fig. 5, and extending partly or entirely across the face of the bung, parallel to the grain thereof. It will thus be observed that a bung constructed according to my invention not only retains all of the advantages derived from the style of incision, as heretofore described in my Letters Patent No. 268,026, but also adds greater strength and efficiency to the bung while used as such; and

it also possesses greater strength as a bung 35 and more efficiency as a bushing than the bungs in which continuous circular incisions are everywhere employed.

What I claim as new and of my invention, and desire to secure by Letters Patent, is— 40

1. A bung having a circular recess or incision, or both, in its top face, and two incisions in its bottom face, the wood between the incisions in the bottom face of the bung remaining intact, the incisions in the opposite faces not 45 penetrating to a common plane, substantially as and for the purposes specified.

2. A bung having a circular recess or incision, or both, in its top face, and two semicircular incisions in its bottom face, the wood between the incisions in the bottom face of the bung remaining intact, the incisions in the opposite faces not penetrating to a common plane, 50 substantially as and for the purposes specified.

3. In combination, a bung having a circular recess or incision, or both, in its top face, and two incisions in its bottom face, the wood between the incisions in the bottom face remaining intact, and a disk of uncut wood, of the diameter of the bung and parallel to the faces of 55 the bung, remaining intact between the inner ends of incisions in the opposite faces of the bung, substantially as and for the purposes specified.

JOSIAH KIRBY.
